(57) **CLAIM**

I claim the ornamental design for a scissor handle attachment, as shown and described.

DESCRIPTION

FIG. 1 is a perspective view of the scissor handle attachment shown attached to a pair of scissors, in the hand of a user;

FIG. 2 is a front end view of the scissor handle attachment;

FIG. 3 is a back end view thereof;

FIG. 4 is a right side view thereof;

FIG. 5 is a left side view thereof;

FIG. 6 is a top plan view thereof; and,

FIG. 7 is a bottom plan view thereof.

The broken line showing of the hand and scissors are for illustrative purposes only and form no part of the claimed design.
